CLAIM

I claim the ornamental design for a multipurpose tool, as shown and described.

DESCRIPTION

FIG. 1 is a perspective view of a multipurpose tool according to the present invention.

FIG. 2 is a top plan view of the multipurpose tool of FIG. 1.

FIG. 3 is a bottom plan view of the multipurpose tool of FIG. 1.

FIG. 4 is a rear elevational view of the multipurpose tool of FIG. 1.

FIG. 5 is a front elevational view of the multipurpose tool of FIG. 1.

FIG. 6 is a first side elevational view of the multipurpose tool of FIG. 1; and,

FIG. 7 is a second side elevational view of the multipurpose tool of FIG. 1.
